CLAMP FOR CEMENT FORM PANELS

Arthur J. Harder, Chicago, Ill.

Application April 4, 1947, Serial No. 739,309

10 Claims. (Cl. 25—131)

1

The present invention relates to panel clamps. In building concrete walls a plurality of panels, usually of rectangular formation and made of plywood, is used. Such panels are arranged in an edge to edge position on each side of a concrete wall to be built, with the two planes of the panels arranged parallelly and maintained in mutually rigid condition to receive cement mixture, which upon its setting forms a concrete wall. Usually said panels, along their margins are provided with metallic angle members which in a pair of adjacent panels are rigidly engaged for maintaining the adjacent panels in an interlocked rigid mutual relation for forming a form on each side of a concrete wall to be built preparatory to the cement pouring operation. Therefore, the principal object of the present invention is the provision of a suitable clamp, of a comparatively simple construction for engaging the angle members in the adjacent panels for maintaining the latter in a rigid mutual position, and which are easy to apply to said angle members when the form is being built, and which are easy to disengage when the cement has solidified, preparatory to the dismantling of the form.

Usually a pair of spaced form walls built of the panels aforesaid are maintained in a rigid mutual position by a plurality of metallic ties, positioned transversely of the built form. Such ties are usually rigidly connected to each panel wall for maintaining the two in a rigid mutual position for preventing yielding when under the pressure of the poured cement. The ties are usually provided at their ends with a rather complicated mechanism for engaging the form walls. The ties necessarily remain embedded in the concrete wall when panels forming form wall on each side thereof are removed therefrom after first disengaging the same from their interlocked position with the panels. Therefore, another object of the present invention is the provision of a clamp which while engaging the angle members aforesaid, is capable of engaging the tie at the same time and of locking the latter to the panels. Thus, the present clamp has considerable advantage over those used at present, because it performs double function, namely, interlocks the adjacent panels at their joints formed by a pair of said angle members, and engages the tie in a rigid grip and holds the same in a rigid interlocked position with relation to the panel. This double function is performed by a single operation as the tie is applied to the form. Also, the disengaging operation of the clamp from the form simultaneously releases its hold upon the panel joint as well as upon the tie.

With the above general objects in view and others that will appear as the invention is better understood, the same consists in the novel construction, combination and arrangement of parts

2

hereinafter more fully described, illustrated in the accompanying drawing and pointed out in the appended claims.

In the drawing forming a part of this application and in which like designating characters refer to corresponding parts throughout the several views:

Fig. 1 is a top elevational view of the clamp in its operative position with the panel joint and a tie;

Fig. 2 is a side elevational view of the clamp in the same position;

Fig. 3 is an edge elevational view thereof; and Fig. 4 is a cross-sectional view thereof on line 4—4 of Fig. 2.

Referring to the present drawing there is shown a plurality of panels 10 arranged in an edge to edge position for providing a form wall on each side of a concrete wall to be built. When a pair of such form walls is constructed cement 11 is poured therebetween which upon setting forms a concrete wall. When the cement has solidified the form walls built of said panels 10 is dismantled and taken away from the finished concrete wall.

Said panels 10 are usually made of plywood and each is of a rectangular formation. Each of said panels 10 is ordinarily provided with angle member 12 rigidly affixed to the panel and adjacent its margins on all four sides thereof. Portions of said angle members 12 which are in a vertical relation with the body of the panels form a joint in two adjacent panels which when rigidly engaged will maintain the adjacent panels in an interlocked rigid mutual position. The joint referred to is indicated by 13.

A plurality of ties 14 are applied to a pair of form walls consisting of said panels 10 and by each of their ends bound to each form wall for maintaining the two in a rigid mutual position, preventing their yielding away from each other when under pressure of the cement poured therebetween or during the setting thereof. Each of said ties 14 is preferably made of metal and has a form of an oblong narrow strip and comparatively thin. The length of each tie 14 corresponds to the combined width of the space between the form walls, the thickness of the panels and the width of the outwardly projecting portions of angle members 12.

The clamp constituting the subject-matter of the present invention is designed for the purpose of interlocking joint 13 defined by the outwardly projecting portions of the adjacent angle members 12 in any adjacent pair of panels 10 when laid in an edge to edge relation on a common plane, as seen in Fig. 1, and for engaging the end of tie 14 for rigidly binding the same to joint 13 and thereby to the form wall defined by a plurality of panels 10 arranged in a co-

planary relation, on each side of a concrete wall to be built, and includes a substantially U-shaped housing 15. The latter is formed of side walls 16 and 17, which by one of their ends are connected by end wall 18. Side wall 16 terminates on the plane of the outer terminations of angle members 12 when the clamp is in an operative position with joint 13, as best seen in Fig. 4, while side wall 17 is extended farther and on its inner face is provided with an integrally formed and laterally directed lug 19, which contacts with and bears against the adjacent face of one angle member 12 when the clamp is in an operative position with joint 13, as seen in Fig. 4.

Integrally formed with said housing 15, adjacent its lower end, and downwardly depending therefrom is block 20, the rear end of which connects with the lower end of rear wall 18 and the adjacent portions of side walls 16 and 17 through horizontal wall 21 which is provided with aperture 22 for the purpose later described. The width of said block 20 is narrower than the width of said housing 15, one side wall thereof being the downward continuation of side wall 16, while the opposite side wall thereof is spaced away from the adjacent side wall 17 of housing 15 and disposed nearer towards the center of the clamp as seen in Fig. 3. The upper front portion of block 20, between walls 16 and 17, remains flush with the corresponding termination of side wall 16, as at 23, so that the former remains in contact with joint 13 in the operative position of the clamp therewith, as seen in Figs. 2 and 4. However, the lower front portion of said block 20 terminates short of the free end of joint 13, effecting recess 24 therewith for the purpose later described.

Longitudinally, centrally and on a vertical plane said block 20 is provided with recess 25 for receiving therewithin lower, stationary, tie-engaging jaw 26. Said recess 25 does not bisect the rear wall of said block 20, so that said jaw 26 bears thereagainst, as is seen in Fig. 2. Said jaw 26 is rigidly anchored within block 20 and housing 15 by means of a pair of pins 27 and 28, the former passing through side walls 16 and 17 of housing 15, the upper end of block 20 and said jaw 26, while the latter passing through the lower end of block 20 and jaw 26, both in a transverse relation.

To digress at this point from a further description of the clamp, tie 14, adjacent its end and along its edges is provided with opposed teeth 29. The tie by its end, including teeth 29, is receivable between the adjacent angle members 12 at joint 13, thereby maintaining said angle members 12 and the margins of adjacent panels in a spaced relation. The spaces defined thereby are very narrow corresponding to the width of tie 14, which however are not sufficiently wide to permit leakage of the cement to any undesirable degree.

As is clearly seen in Fig. 2, said stationary jaw 26 enters by its free end into the recess defined by the adjacent portions of angle members 12, and from one edge of tie 14 to engage the adjacent teeth 29 by correspondingly formed teeth 30 upon the upper edge of said jaw 26.

Receivable between walls 16 and 17 of housing 15, and above the upper end of block 20 is the inner end of shank of lever 31, which is journaled upon pivot pin 32 for angular shifting movement. One face of said lever 31 contacts the inner face of said side wall 16 of housing 15, while the opposite face thereof is in a spaced relation with the adja-

cent inner face of side wall 17, and in order to substantially completely fill the space between said walls 16 and 17, and to prevent thereby said lever 31 from lateral shifting movement upon pin 32 the same is provided with an integrally formed and laterally projecting hub 33, which is interposed between the body portion of said lever 31 and wall 17, allowing however sufficient space for seating between said hub 33 and wall 17 of L-shaped leaf spring 34, for the purpose hereinafter specified.

Said lever 31 is longitudinally and centrally recessed for receiving therewithin jaw 35 which is rigidly affixed to said lever by means of a pair of transverse pins 36 passing through said lever 31 and said jaw 35. Said jaw is provided on its inner edge with teeth 37 for engaging the adjacent teeth 29 made in tie 14. Both said jaws 26 and 35 are in alinement and of the same width corresponding to the width of tie 14, and both are adapted to enter the recess between angle members 12, and to engage said tie from the opposite edges through teeth 29 made in the tie and correspondingly formed teeth 30 and 37 made in jaws 26 and 35, respectively.

The upper free end of lever 31 has a laterally enlarged head 38, from which a pair of spaced joint-engaging extensions 39 project. The inner faces of said extensions are at opposed inclines as at 40, thereby effecting substantially V-shaped recess within which the free end portions of angle members 12 at joint 13 are receivable. Due to said inclined faces 40, when pressure is applied to head 38, the adjacent pair of free portions of angle members 12 are flexed toward each other, as their outer faces are forced to ride upon the inclined inner faces of said extensions 39, until joint 13 is forced into the recess defined by said extensions 39, thereby effecting a rigid and tight interlocking between extensions 39 and joint 13. It is of course assumed that during the above operation the clamp is already in engagement with tie 14 by virtue of the engagement of teeth 30 in stationary jaw 26 with teeth 29 in tie 14.

Lever 31 is capable of angular shifting movement upon pin 32 as is indicated by dotted lines in Fig. 2, and when said extensions 39 are brought to an operative position with joint 13, as aforesaid, and as shown in full lines in Fig. 2, said jaw 35 is simultaneously shifted into the recess defined by a pair of free portions of adjacent angle members 12 until teeth 37 thereof spring into engagement with teeth 29 at the edge of said tie 14 opposite from that at which jaw 26 engages the same. When both jaws 26 and 35 are in engagement with tie 14, extensions 39 are rigid with joint 13, and the clamp is in an interlocked relation with said tie 14 and joint 13, and no ordinary jarring will suffice to dislodge the interengagement.

When the concrete wall has set and the form walls are ready to be removed therefrom, a crowbar or similar instrument is inserted between tongue 41 and the adjacent edges of angle members 12, and angularly shifted until teeth 37 of jaw 35 are forced out of engagement with teeth 29 in tie 14. When this is accomplished extensions 39 are then shifted away from joint 13. Push of the clamp in a direction which tends to separate jaw 26 from tie 14 will disengage the former from the latter. To accomplish this object clamp may be angularly shifted by any suitable instrument in the direction which will close recess 24 by bringing the adjacent face of block 20 in contact with joint 13, or block 20 may

be hit by a hammer at its outer end wall; the space defined by recess 24 will permit angular shifting of said block 20 and of the clamp for dislodging jaw 26 from its engagement with the teeth in tie 14. When this is done the clamp will be completely disengaged from joint 13 as well as from tie 14, and when all clamps are removed from all panels 10 and ties 14, said panels 10 are then ready to be taken away from the completed concrete wall.

When the clamp remains in an engagement with joint 13 through extensions 39, to guard against accidental opening of the clamp, that is against angular shifting of lever 31 away from joint 13, a nail or spike may be inserted into aperture 22, which, bearing against lever 31 or head 38, or being in the path thereof, will prevent the angular shifting of said lever 31 and of the head 38, and consequent disengagement of extensions 39 from joint 13.

Referring to spring 34, its body portion is interposed between hub 33 and the adjacent face of side wall 17, and rests by its one edge upon the inner end of block 20. Pin 32 also passes through it and maintains it in stationary position. The operative end of said spring 34, substantially in a perpendicular relation with the body portion thereof, is positioned for flexing movement above the upper end of block 20 and within the space defined by the free ends of walls 16 and 17, lug 19, adjacent end of lever 31 and hub 33. The outer termination of said operative end of spring 34 tends to flex beyond the plane of the free end of wall 16, and has loop 42 which normally extends beyond the said plane, being urged into that position by the inherent flexing action of the said operative end of said spring 34. The space defined as aforesaid affords the room for flexing action of the said operative end of said spring 34.

Cooperating with the free end of wall 17 and lug 19 is screw 43 having knurled knob 44. Assuming that one panel 10 has already been set in a vertical position at the commencement of form wall erecting operation, with no side panel on the side thereof in an edge to edge relation, tie 14 is first applied to said panel 10 in an edge contact therewith and at the vertical edge thereof, the same being of course in contact with the outwardly projecting leg of angle member 12. While manually holding the tie in that position, with the end thereof flush with the outer edge of the outwardly extending leg portion of said angle member, as is seen in Fig. 4, the clamp is then applied to the said leg portion and tie 14, by bringing the stationary jaw 26 below the lower edge of tie 14 for engaging teeth 30 with the corresponding teeth 29 in tie 14, as seen in Fig. 2. In this position of the clamp the free end of wall 17 will remain in a transverse relation with the outwardly extending leg portion of said angle member 12, with lug 19 in the proximity of the adjacent face of said outwardly extending leg portion of angle member 12, as is seen in Fig. 4. Thereupon screw 43 is tightened by turning knob 44 for bringing the free, inner end of said screw 43 in engagement with said adjacent face of the outwardly extending leg portion of member 12, as is apparent from the showing in Fig. 4. In cooperation with said lower, stationary jaw 26 said screw 43 clamps the interposed outwardly extending leg portion of said angle member 12, for maintaining the entire clamp in a rigid association with a single outwardly extending leg portion of angle member 12 of that one panel 10 already set up in a vertical position while com-

mencing the erection of form wall aforesaid. The identical procedure for affixing the clamp through the medium of screw 43 and for engaging jaw 26 with the lower edge of tie 14 at one end thereof simultaneously takes place at the opposite end of tie 14 at the other opposite form wall being formed in the spaced relation with the first one, thereby supporting said tie 14 at both of its ends upon jaws 26 in the two clamps employed.

From the hereinabove description it will therefore be apparent that due to the procedure last hereinabove described the clamp is already in an engagement with the outwardly extending leg portion of angle member 12 in single panel 10, with tie 14 supported on a vertical plane by means of jaw 26 engaging said tie 14 at its lower edge. The lateral support of tie 14, and the contact thereof with the adjacent edge of panel 10 and with the outwardly extending portion of angle member 12, is had through the medium of loop 42 of the operative end of spring 34, as is clearly seen in Fig. 4.

While the clamp is maintained in a rigid engagement with the outwardly extending leg portion of angle member 12 of a single panel 10, as aforesaid, the next panel 10 is bodily brought to the first one to lay the two in an edge to edge relation. Said last named panel 10 is preferably brought to the first one from within the space defined by two form walls being constructed, that is from the space into which eventually the cement will be poured upon completion of the erection process of a pair of form walls. The shifting of said latter panel 10 into its operative position with relation to the first one, will bring the outwardly extending leg portions of angle members 12 in the two panels into a mutual, cooperative position for forming joint 13, as seen in Fig. 1. During the shifting of said last named panel into its cooperative relation with the first one, the outwardly extending leg portion of angle member 12 of said last named panel 10 will strike loop 42 of spring 34, deflecting the operative end thereof away from the adjacent edges of joint 13. At this point the function of said loop 42 terminates, because the adjacent edge of newly positioned panel 10 with the outwardly extending leg portion of its angle member 12 will provide lateral support for tie 14. When joint 13 has been formed spring 34 is deflected as aforesaid and remains inoperative, while screw 43 will continue to remain in its engagement with the adjacent face of the outwardly projecting leg portion of angle member 12 with which the same was originally brought into engagement, for preventing the downward shifting of jaw 26 and the disengagement of its teeth with teeth 29 at the lower edge of tie 14.

While said engagement of lower jaw 26 with tie 14 is maintained as aforesaid, lever 31 is shifted upon its pivot pin 32 for bringing head 38 into its operative position with the newly formed joint 13, with extensions 39 in an operative position with said joint 13, as indicated by full lines in Fig. 2.

Although all clamps are of identical construction, all having springs 34, and are to be used interchangeably, and without regard as to whether the same are applied at vertical or horizontal joints 13 formed by a pair of adjacent angle members 12, spring 34 with its loop 42 has no actual function when the clamp is used in connection with horizontal joints 13, because ties 14, resting upon the horizontal edges of a pair of oppositely disposed panels 10 in a pair of spaced form walls

under construction, need no preliminary lateral support as ties 14 at the vertical edges of panels 10 do.

When jaws 26 and 35, and their respective teeth 30 and 37, become damaged or worn out the jaws may be removed from block 20 and lever 31, respectively, upon removal of pins 27, 28 and 36, and new jaws substituted in their stead.

When concrete wall has been built between a pair of spaced form walls made of panels 10, one on each side of a concrete wall, said form walls will then be ready to be dismantled and panels 10 removed from the finished concrete wall. To dismantle the form walls, first the clamps are removed from all joints 13, and this is done by first removing nail or spike from aperture 22. Then head 38 with extensions 39 is shifted out of engagement with joint 13, which operation simultaneously disengages jaw 35 from engagement with the teeth at the adjacent edge of tie 14. Thereupon screw 43 is disengaged from the adjacent outwardly projecting leg portion of angle member 12. When all of said clamps have been removed from their joints 13, with stationary jaws 26 pried out of engagement with teeth 29 of tie 14, by hitting the end wall of block 20 with a hammer, thereby permitting shifting of the clamps to the extent allowed by recess 24, as hereinabove described, all panels 10 are then removed from contact with the finished concrete wall and on both sides thereof. This operation will expose the ends of ties 14 which prior thereto were within joints 13 of panels 10.

Notches 45 are made in tie 14, at the adjacent portions thereof which are in the proximity of the lateral surfaces of the concrete wall. By striking at the exposed ends of ties 14 and preferably upon the edges thereof, by a hammer, the tie will break along the line of a pair of opposed notches 45. The resulting crevice made in the concrete wall may be filled with cement in order to make the surfaces of the concrete wall smooth. Of course, the central portions of ties 14, upon breaking their ends as aforesaid, will remain embedded within the concrete wall.

From the hereinabove description it will be apparent that during the construction of form walls on each side of a concrete wall to be built, no difficulty will be encountered in applying jaws 26 and 35 to their engagement with the respective teeth 29 in tie 14. When however cement has been poured between a pair of erected form walls, the same will exert pressure in lateral direction and upon the inner faces of panels 10 in the two form walls. This pressure will tend to draw each pair of the opposed clamps cooperating with each tie into the opposite directions and in a longitudinal direction with relation to tie 14, thereby tending to increase the grip of jaws 26 and 35 by their respective teeth 30 and 37 upon teeth 29 at each end of tie 14. The greater this pressure, the greater the gripping engagement between jaws 26 and 35 with each end of tie 14. Due to this reason it is necessary to use an instrument by interposing the same between tongue 41 and the adjacent edge of joint 13 to swing lever 31 away from joint 13 and extensions 39 out of their operative engagement therewith, as well as to pry jaw 26 out of engagement with the opposite teeth at tie 14 by hitting the end wall of block 20 by a hammer, as a preliminary step to the removal of the clamp from joint 13.

If preferred, the marginal edges of panels 10 may be slightly extended beyond the outer plane of the outwardly extending leg portion of angle

members 12, with recesses 46 made in the margins of panels 10 for accommodating therewithin tie 14. Said extended marginal portions of panels 10 will contact in a pair of adjacent panels 10, along line 47, the two panels accommodating tie 14 within their recesses 46, thereby avoiding the crevice between the adjacent panels and completely preventing leaking of the cement.

While there is described herein a preferred embodiment of the present invention, it is nevertheless to be understood that minor changes may be made therein without departing from the spirit and scope of the invention as claimed.

What I claim as new is:

1. A clamp of the class described comprising a base, a jaw in a stationary relation therewith, a swingable member in a pivotal relation with said base, a pair of clamping members at the free end of said swingable member, and a jaw connected with said swingable member intermediately of said base and said clamping members, said jaws being on a plane substantially median of said clamping members.

2. A clamp of the class described comprising a base, a jaw in a stationary relation therewith, a swingable member in a pivotal relation with said base, a pair of clamping members at the free end of said swingable member, and a jaw connected with said swingable member intermediately of said base and said clamping members, the operative edges of said jaws remaining substantially in a parallel relation when said swingable member is swung into an operative position, said jaws being on a plane substantially median of said clamping members.

3. A clamp of the class described comprising a base, a jaw in a stationary relation therewith, a swingable member in a pivotal relation with said base, a pair of clamping members at the free end of said swingable member, a jaw connected with said swingable member intermediately of said base and said clamping members, a projection extending from said base in a substantially parallel relation with said first named jaw, and an adjusting member in said projection coacting with said first named jaw in a transverse relation therewith.

4. A clamp of the class described comprising a base, a jaw in a stationary relation therewith, a swingable member in a pivotal relation with said base, a pair of clamping members at the free end of said swingable member, a jaw connected with said swingable member intermediately of said base and said clamping members, the operative edges of said jaws remaining substantially in a parallel relation when said swingable member is swung into an operative position, a projection extending from said base in a spaced relation with said first named jaw, and an adjustable clamping screw in said projection coacting with said first named jaw in a plane perpendicular to the plane upon which both of said jaws coact.

5. A clamp of the class described comprising a base, a jaw in a stationary relation therewith, a swingable member in a pivotal relation with said base, a pair of clamping members at the free end of said swingable member, a jaw connected with said swingable member intermediately of said base and said clamping members, said jaws being comparatively thin and being arranged on a plane running through the longitudinal center of said swingable member, a projection extending from said base in a spaced relation with said first named jaw, an adjustable clamping member in said projection coacting with said first named jaw in a transverse relation to said first named

plane, and a yieldable retaining member connected to said base, said yieldable retaining member being on a plane coextensive with the plane of the face of said first named jaw which is opposite from the plane which is coextensive with the face thereof adjacent said projection.

6. In a concrete form, including a pair of spaced form walls for receiving therebetween cement mixture which upon setting forms a concrete wall, a plurality of panels, said panels defining said form walls when arranged in an edge to edge relation, a plurality of ties, each of said ties consisting of an oblong, comparatively narrow strip of material, each end of each tie being passed between a pair of adjacent panels in each form wall, the wider faces of said ties being in contact with the adjacent edges of a pair of adjacent panels at each end of each tie, the edges of the adjacent pair of panels effecting a recess corresponding in width to the thickness of the tie therebetween, a clamping member insertable within said recess for engaging each tie at the opposite edges thereof, and means associated with said clamping member for binding the latter to said adjacent pair of panels at each form wall.

7. In a concrete form, including a pair of spaced form walls for receiving therebetween cement mixture which upon setting forms a concrete wall, a plurality of panels, said panels defining said form walls when arranged in an edge to edge relation, a plurality of ties, each of said ties consisting of an oblong, comparatively narrow strip of material, each end of each tie being passed between a pair of adjacent panels in each form wall, the wider faces of said ties being in contact with the adjacent edges of a pair of adjacent panels at each end of each tie, the edges of the adjacent pair of panels effecting a recess corresponding in width to the thickness of the tie therebetween, a clamping member, a pair of jaws associated therewith, said jaws being insertable within said recess for gripping each tie at the opposite edges thereof, and means associated with said clamping member for binding the latter to said adjacent pair of panels at each form wall.

8. In a concrete form, including a pair of spaced form walls for receiving therebetween cement mixture which upon setting forms a concrete wall, a plurality of panels, said panels defining said form walls when arranged in an edge to edge relation, an angle member rigidly affixed to each panel adjacent the margin thereof, the outwardly extending leg portion of said angle member in each panel being substantially in a perpendicular relation with the body of the panel, a plurality of ties, each of said ties consisting of an oblong, comparatively narrow strip of material, each end of each tie being passed between the outwardly extending leg portions of said angle members in each pair of adjacent panels in each form wall, whereby said outwardly extending leg portions of said angle members contact with the wider faces of each of said ties, and define a recess corresponding in width to the thickness of the retained tie, a clamping member, a pair of jaws carried by said clamping member, said jaws entering said recess for gripping each end

of each tie adjacent the opposite edges of each tie, and means associated with said clamping member for rigidly engaging on a transverse plane a pair of the adjacent outwardly extending leg portions of said angle members in a pair of adjacent panels for binding the tie to the latter and for maintaining a pair of adjacent panels in a rigid operative relation.

9. In the art of setting up form walls for receiving therebetween a cement mixture which on setting forms a concrete wall, a plurality of ties for maintaining a pair of form walls in a spaced, bound relation, a plurality of panels, which, when arranged in an edge to edge relation defining one of said form walls, a base member, means associated therewith for temporarily supporting the same upon one of said panels, means carried by said base member for temporarily laterally engaging the tie and holding the same in contact with a vertical edge of said one panel, as the adjacent panel is brought to said one panel in an edge to edge relation said newly set panel rendering said last named means inoperative, the tie being then laterally supported by the two panels, means carried by said base member for rigidly engaging the end of the tie, and means for rigidly engaging said base member with the two set panels.

10. In the art of setting up form walls for receiving therebetween a cement mixture which on setting forms a concrete wall, a plurality of ties for maintaining a pair of form walls in a spaced, bound relation, a plurality of panels, which, when arranged in an edge to edge relation defining one of said form walls, a base member, means associated therewith for temporarily supporting the same upon one of said panels, means carried by said base member for temporarily laterally engaging the tie and holding the same in contact with a vertical edge of said one panel, as the adjacent panel is brought to said one panel in an edge to edge relation said newly set panel rendering said last named means inoperative, the tie being then laterally supported by the two panels, means carried by said base member for rigidly engaging the end of the tie through the recess formed by the edges of the two adjacent panels resulting from the interposition of the tie therebetween, and means for rigidly engaging said base member with the two set panels for binding the tie thereto and for mutually interlocking the two set panels.

ARTHUR J. HARDER.
